UNITED STATES PATENT OFFICE.

ELMER S. HARRIS, OF HAVERHILL, MASSACHUSETTS.

DESIGN FOR A TRIMMING-KNIFE.

SPECIFICATION forming part of Design No. 25,098, dated January 28, 1896.

Application filed November 13, 1895. Serial No. 568,869. Term of patent 14 years.

To all whom it may concern:

Be it known that I, ELMER S. HARRIS, a citizen of the United States, residing at Haverhill, in the county of Essex and State of Massachusetts, have invented and produced a new and original Design for Trimming-Knives, of which the following is a specification, reference being had to the accompanying drawings, showing a part thereof.

- 10 Figure 1 is an edge view of a trimming-knife, showing my design. Fig. 2 is a side elevation of the same, and Fig. 3 is a perspective view, a part of the knife being broken away.
- 15 The leading feature of my design consists in a cylindrical or annular knife having a thickened portion with substantially parallel inner and outer surfaces at its outer edge, an adjacent thinner portion also having substantially parallel inner and outer surfaces forming shoulders at the junction of the two

portions and a tapered portion at the other edge.

In the drawings, a represents an annular knife having a tapered cutting-edge a' .

b represents the thickened portion of the knife, said portion including the back or outer edge of the knife and extending therefrom to shoulders b' b'' which define the inner margin of the said thickened portion and the beginning of the intermediate thinner portion.

I claim—

The design for a trimming-knife substantially as shown and described.

In testimony whereof I have signed my name to this specification, in the presence of two subscribing witnesses, this 26th day of October, A. D. 1895.

ELMER S. HARRIS.

Witnesses:

C. F. BROWN,
A. D. HARRISON.
